United States Patent Office

Des. 178,082

Patented June 19, 1956

178,082

COIN SAVINGS BANK OR SIMILAR ARTICLE

Bernard Piermont, San Diego, Calif.

Application November 7, 1955, Serial No. 38,781

Term of patent 14 years

(Cl. D34—11)

Fig. 1

Figure 1 is a side elevational view of a coin savings bank or similar article, showing my new design;

Fig. 2 is a top plan view thereof, the flags being omitted for convenience of illustration.

I claim:

The ornamental design for a coin savings bank or similar article, as shown and described.
